FLEXIBLE CONTAINER FOR PILLS OR THE LIKE

William C. Bundy, Playa Del Rey, Calif.
(507 S. Douglas St., El Segundo, Calif. 90245)

Filed Dec. 15, 1966, Ser. No. 5,048

Term of patent 7 years

(Cl. D58—12)

FIG. 1 is a top plan view of a flexible container for pills or the like showing my new design;

FIG. 2 is a side view thereof;

FIG. 3 is a bottom view thereof; and

FIG. 4 is an end view thereof.

I claim:

The ornamental design for a flexible container for pills or the like, as shown.
